UNITED STATES PATENT OFFICE.

CHARLES F. STODDARD, OF NEW YORK, N. Y., ASSIGNEE TO AMERICAN PIANO COMPANY, OF NEW YORK, N. Y., A CORPORATION OF NEW JERSEY.

AUTOMATIC MUSICAL INSTRUMENT.

1,360,049.

Specification of Letters Patent. Patented Nov. 23, 1920.

Application filed March 7, 1918. Serial No. 220,940.

To all whom it may concern:

Be it known that I, CHARLES F. STODDARD, a citizen of the United States of America, and a resident of the city, county, and State 5 of New York, have invented an Improvement in Automatic Musical Instruments, of which the following is a specification.

This invention relates to automatic musical instruments such as player pianos, and 10 pertains more particularly to mechanism for controlling the operation of the note sheet winding and rewinding apparatus. The principal object of the invention is to provide apparatus for automatically controlling 15 the winding and rewinding of the note sheet and to effect a repetition of the composition if desired; such apparatus being preferably combined with means for stopping the driving motor.

20 A preferred embodiment of the invention has been selected herein for illustration and description and is shown in the accompanying drawings, wherein,

Figure 1 is an elevation of a portion of a 25 player piano, showing an assembly of illustrative apparatus embodying the present invention.

Fig. 2 is a plan view of the key rail showing suitable hand control levers.

30 Fig. 3 is a diagrammatic representation of the controlling mechanism shown in Fig. 1, and

Fig. 4 is a detail view of one element of the controlling mechanism.

35 Referring to Fig. 1 of the drawings, 10 designates the key bed of a typical player piano above which boards 11 and 12 conceal the usual pneumatic action. Located above the pneumatic action is a spool box 13 having a tracker bar 14 provided with vents 40 which are connected with the player pneumatics in the usual manner. Journaled in the spool box in the usual manner is a take-up roll 15, while above the tracker bar are 45 the usual bearings 16 and 17 between which a music spool 18 may be placed so that a note sheet 19 may be fed back and forth between the note sheet spool and the take-up roll.

50 To drive the take-up roll there is provided a gear 20 fast thereto and adapted to mesh with a pinion 21 carried by a longitudinally slidable shaft 22 journaled in a frame 23 fastened to the side of the spool box. The 55 shaft 22 carries a sprocket 24 at its outer

end, which is connected by a chain 25 with a sprocket 26 fast to a shaft 27 of a wind motor 28. Loosely mounted upon the shaft 22 inside the vertical frame of the bracket 23 is a sprocket 29. This sprocket is connected by a chain 30 with a sprocket 31 fast to a shaft 32 which is attached directly to the right hand spool bearing 17. The shaft 32 is suitably journaled in the frame 23.

A clutch mechanism of the usual type is 65 provided to connect the motor alternatively with the take-up roll or note sheet spool; the same being herein shown as a collar 33 fast to the shaft 22 and provided with a pin 34 which may engage a pin 35, projecting 70 inwardly from the sprocket 29, when the shaft 22 is moved to the right to disengage the pinion 21 from the gear 20. A clutch lever 36 is pivoted at 37 to the frame 23 and is connected by a link 38 with a vertical 75 shaft 39 which in turn is connected by a link 40 with a reversing lever 41 pivoted at 42 to the key bed.

With the parts in the position shown, that is, with the reverse lever thrown to the right 80 the operation of the wind motor will rotate the take-up roll to wind the note sheet thereon. When the reverse lever is thrown to the left the clutch lever 36 will move the shaft 22 to the right thus disengaging the pinion 85 21 from the gear 20 and engaging the pins 34 and 35 to drive the note sheet spool and rewind the note sheet thereon.

Power is supplied to the wind motor 28 by an exhaust apparatus of any practicable 90 type here shown as located within a casing 50 and driven through a fly wheel 51 which is connected by a belt 52 with an electric motor 53. An exhaust chest 54 is located upon the exhaust apparatus casing and wind trunks 95 55 and 56 lead to the action wind chest and to the wind motor.

The electric motor 53 may be placed in circuit with a suitable source of electricity and feed wires may be connected at 57. One 100 wire 58 from the socket 57 may be connected with a switch 59 and the other wire 60 connected directly to the motor. The movable contact member 61 of the switch may be connected with the motor through a wire 62. 105 A switch handle 63 may be located conveniently upon the key rail, pivoted at 64 and connected with the movable contact member of the switch by a rod 65. With the switch lever 63 in the position shown, the switch 110

will be closed and the exhausting apparatus driven by the electric motor. When the switch lever 63 is thrown to the right the switch is opened and the motor will stop.

5 In instruments of the character referred to herein, it is desirable to provide means for automatically reversing the direction of the feed of the note sheet at the end of the composition, and thereafter, when the note 10 sheet has been completely rewound, for automatically stopping the electric motor. It is also desirable to provide means for automatically repeating the playing of a composition when desired. The parts of the 15 herein disclosed apparatus embodying these automatic features will be described in the sequence indicated.

Referring particularly to Fig. 3, which is 20 a diagrammatic representation of the parts now to be described, and referring only to Fig. 1 to indicate a preferred assembly, it will be seen that the reverse lever 41 is provided with a cross-arm 75 which is engaged 25 at the right of the pivot 42 by the movable board of a pneumatic 76 and at the left by the movable board of a pneumatic 77. These pneumatics are provided for automatically throwing the lever 41 from one side to the other; the collapse of the pneumatic 76 being adapted to move the lever 41 to the playing 30 position and the collapse of the pneumatic 77 being adapted to move the lever 41 to the reverse position.

The pneumatic 77, which is adapted to 35 reverse the travel of the note sheet, is in communication through a duct 87 with a valve chamber 89 having a port 90 to atmosphere and a port 91 to an exhaust chamber 92 which is connected by a duct 93 with the 40 main exhaust chest 54. A valve 94 is mounted within the valve chamber 89 and has a stem resting upon a diaphragm 95 of a diaphragm chamber 96. The diaphragm chamber 96 is connected by a channel 97 45 with a valve chamber 98 having a port 99 to the exhaust chamber 92. A duct 100 opens into the valve chamber 98 at a point where it is adapted to be closed by a valve 101 mounted therein.

50 For the present the valve 101 may be disregarded and it may be assumed that ducts 97 and 100 are directly connected. The office of the valve 101 will be later described.

The duct 100 opens to a valve chamber 102 55 having a port 103 to atmosphere and a port 104 to the exhaust chamber 92. A duplex valve 105 is mounted within the valve chamber 102 and is adapted to open ports 103 and 104 alternatively. This valve 105 rests 60 upon a diaphragm 106 over a diaphragm chamber 107 which is connected by a duct 108 with a vent 109 in the tracker bar. This tracker vent is so located that it will 65 not be opened by any of the note perforations but may be opened by a per-

foration properly located. If, therefore, a perforation is placed in the note sheet near the end thereof so that it will reach the tracker bar after all the note perforations have passed, the vent 109 may be 70 opened to admit atmosphere and operate the train of valve mechanism to connect pneumatic 77 with the exhaust chest 54, throw the lever 41 to the rewind position, thus connecting the wind motor 28 with the note 75 sheet spool to rewind the note sheet thereon.

The operation of the valve mechanisms will be apparent to those skilled in the art from the following brief description. Atmosphere being admitted to duct 108 will 80 permit diaphragm 106 to rise, close port 104, open port 103 and admit atmosphere to duct 100 which, being in communication with duct 97 and diaphragm chamber 96, will 85 admit atmosphere to that chamber and permit valve 94 to be raised closing atmosphere port 90 and opening exhaust port 91. This will place the interior of pneumatic 77 in communication with the exhaust chest 92 through the duct 87 whereupon the pneumatic 77 will be collapsed and throw the reverse lever to the left as previously described.

Having thus described the automatic reversing mechanism the electric motor stop 95 mechanism will now be described.

The movable board of a pneumatic 110 is attached to the switch lever 63 by a link 111; this pneumatic being adapted to throw the lever to the right when it is collapsed and thus open the electric circuit through the motor. The interior of the pneumatic 110 is in communication, through a duct 112, with a valve chamber 113 having a port 114 to atmosphere and a port 115 to an exhaust 100 chamber 116 which is connected to the main exhaust chest 54 by a duct 120. A valve 117 is mounted in the valve chamber 113 and its stem rests upon a diaphragm 118 over a diaphragm chamber 119. The diaphragm 110 chamber 119 is connected by a duct 121 with a switch valve 122 which comprises a cylindrical casing 123 having a rotatable valve member 124 fast to a handle 125 projecting through the key bed. The valve casing 123 is provided with the central port 126, which may be connected alternatively with adjacent ports 127 and 128. In the position shown the duct 121 is in communication with a duct 129 through ports 126 and 127.

115 It will be understood by those skilled in the art that the opening of duct 129 to atmosphere will permit the valve 117 to be raised to close atmosphere port 114 and open exhaust port 115 thereby connecting 120 pneumatic 110 with exhaust chamber 116, collapsing the pneumatic and operating the switch lever to open the electric circuit and stop the motor.

125 Suitable means are provided for opening 130

the duct 129 preferably just before the note sheet has become entirely disengaged from the take-up roll. Such means are herein shown as lever 130, pivoted at 131 to the 5 spool box and alined with an annular groove 132 formed preferably toward one end of the take-up roll. This stop lever is urged toward the take-up roll by suitable means such as a light spring 133. Mounted at the 10 rear of the spool box is a block 132 having a channel 135 with which the duct 129 is connected. Carried by the lever 130 is a resilient arm 136 which is adapted to close the port 135 when the stop lever 130 is 15 moved to the left a distance slightly less than the difference between the radius of the annular groove and the normal radius of the take-up roll.

It will therefore be apparent that when a 20 note sheet is inserted in an instrument and given a few turns about the take-up roll, the lever 130 will be moved to the left a sufficient distance to close the port 135. When in the operation of the instrument, the 25 note sheet continues to wind upon the spool the lever 130 will be moved still farther to the left but this movement will have no effect as the spring arm 136 will yield, and the port 135 remain closed.

30 It will also be apparent that when, in the rewinding of the note sheet, the annular groove is uncovered so that the lever 130 may move to the right, the port 135 will be open to admit atmosphere to duct 129 35 through the switch valve to duct 121 and to the valve mechanism which operates the pneumatic 110 and opens the electric switch.

Having thus described the automatic reverse mechanism and the automatic stop 40 mechanism, the means herein disclosed to effect the automatic repetition of a composition will now be described.

It has become practically universal practice in the manufacture of note sheets to 45 taper the leading end of the note sheet to a point where a ring or other fastening device is attached for the purpose of engaging the take-up roll. Thus when the note sheet is wound upon the take-up the tapered edges 50 lie upon the spool in a spiral from the point of attachment to the flanges. Therefore as the note sheet is unwound, the surface of the spool adjacent the flange is first uncovered. Thus when the usual note sheet is 55 used in conjunction with the apparatus previously described, the lever 130 will drop into the annular groove 132 and open the port 135 before the note sheet has become disengaged from the spool and substantially 60 at a point in the unwinding of the note sheet indicated in Fig. 4 of the drawings herein. Therefore, if the opening of port 135 is 65 caused to operate the clutch mechanism, specifically to reengage pinion 21 and gear 20, instead of stopping the electric motor the

note sheet will be fed forward again to repeat the playing of the composition embodied in the note playing perforation thereof.

Suitable means are herein provided for attaining this desired object, the same being herein shown as follows: The switch valve 125 if thrown to the left will close port 127 in its casing and connect port 126 with port 128 thereby placing the duct 129 in communication with a duct 150 for the 70 purpose of controlling the repeat mechanism now to be described.

The pneumatic 76 which is adapted to throw the reverse lever to the "play" position is in communication through a duct 80 151 with a valve chamber 152 having a port 153 to atmosphere and a port 154 to the exhaust chest 92. A valve 155 is mounted within the valve chamber 152 and has a stem resting upon a diaphragm 156 of a diaphragm chamber 157. A channel 158 connects the diaphragm chamber 151 with a valve chamber 159 having a port 160 to atmosphere and a port 161 to the exhaust chest 92. A duplex valve 162 is adapted to 90 open ports 160 and 161 alternatively and rests upon a diaphragm 163 of a diaphragm chamber 164. The diaphragm chamber 164 is in communication with a duct 150 through a channel 165. If therefore atmosphere is 95 admitted to the diaphragm chamber 164 by the opening of port 135 valve 162 will be raised to admit atmosphere through channel 158 to diaphragm chamber 157 thus permitting valve 155 to be raised and place 100 pneumatic 76 in communication with the exhaust chest 92, whereupon the pneumatic will be collapsed and throw the reverse lever 41 to the play position thus effecting the 105 automatic reengagement of the wind motor with the take-up roll.

After the operation of the reversing mechanism by the opening of the tracker vent 109, the note sheet may arch up from the tracker bar during rewinding and leave 110 vent 109 open or partially open when stop lever 130 moves forward to open port 135. If this happened with the switch valve in repeat position both pneumatics 76 and 77 would be in communication with exhaust at 115 the same time. Means are therefore provided to insure the effective operation of the repeat mechanism even under such circumstances. As a preferred embodiment of such means I provide a locking valve which will 120 operate upon the opening of vent 135 to shut off communication between the primary valve 105 and the secondary valve 94 of the reverse mechanism. This locking valve is the valve 101 previously referred to.

The valve 101 has a stem resting upon a diaphragm 170 of a diaphragm chamber 171. This diaphragm chamber is in communication with the channel 165 so that simultaneously with the admission of atmosphere 130

to diaphragm chamber 164 to operate the repeat mechanism atmosphere will also be admitted to diaphragm chamber 171 to operate the locking valve. The admission of atmosphere will cause the locking valve to be raised and seat against the upper wall of the valve chamber 98 thus closing duct 100. Thereafter the operation of valve 105 cannot admit atmosphere to the diaphragm chamber of the secondary valve 94. On the contrary diaphragm chamber 96 will be in communication with exhaust chamber 92 through port 99 under the locking valve.

The operation of the apparatus heretofore described may be briefly summarized as follows:—With the electric switch lever in "off" position and the reverse lever in "rewind" position, as indicated in Fig. 2, a note sheet may be inserted in the instrument in the usual manner and given a few turns about the take-up roll. The note sheet will cover and close the reverse operating tracker vent 109 and will throw the lever 130 to the left closing port 135. Then the reverse lever may be moved to the "play" position and the switch to the "on" position which will start the electric motor and the playing of the composition.

If it is desired merely to play the composition once the repeat lever 125 may be left in the position shown in Fig. 1 and in such a case an appropriate perforation in the note sheet at the end of the composition will open tracker vent 109 to operate the reverse mechanism and when the note sheet has been sufficiently rewound to allow the stop lever 130 to drop in the groove 132, the port 135 will be opened to operate the electric switch and stop the motor; the momentum of the moving parts being sufficient to entirely rewind the note sheet upon the music spool.

If, however, at any time before the playing of the composition or during its playing, or during the rewinding, it is thought desirable to repeat the composition, the repeat lever 125 may be thrown to the left thus connecting the duct 135 with the repeat mechanism which will be operated at the appropriate time to reengage the pneumatic motor with the take-up roll and again start the forward feeding of the note sheet. The composition will be repeated as long as the lever 125 is left in repeat position.

It is to be understood that the present invention may be variously modified and embodied within the scope of the subjoined claims.

I claim as my invention:

1. In an instrument of the character described the combination of motor stop mechanism, pneumatic control means governed by the note sheet, note sheet driving means including a clutch, pneumatically operable clutch throwing means, and a valve for con-

nnecting said pneumatic control means alternatively with the motor stop mechanism or the clutch throwing means.

2. In an automatic musical instrument, the combination of a power plant including an electric motor and a switch therefor, switch operating mechanism, note sheet feeding means including a spool and take-up roll, a motor for the note sheet feeding means, clutch mechanism interposed between the said motor and the feeding means, note sheet governed means for operating said clutch mechanism, control means adapted to be operated by the uncovering of the take-up roll, and means to connect said control means alternatively with the clutch operating mechanism or the switch operating mechanism.

3. In an automatic musical instrument the combination of a spool for the note sheet, a tracker, a take-up roll to receive the note sheet from the spool, clutch mechanism, driving means adapted to be connected by said clutch mechanism alternatively with the spool or the take-up roll, pneumatic clutch operating mechanism, governing means for the clutch operating mechanism including tracker controlled means for engaging the driving means with the spool and means co-operating with the take-up roll and rendered operative by the partial uncovering thereof to engage the driving means with the take-up roll, pneumatic motor stop mechanism, and a valve to connect one of the clutch operating elements therewith.

4. In an automatic musical instrument the combination of a spool for the note sheet, a tracker, a take-up roll to receive the note sheet from the spool, a wind motor, a clutch to connect the wind motor alternatively with the spool or take-up roll, a stop mechanism, automatic means to operate the clutch to engage the wind motor with the spool operable by the opening of a tracker vent, means to operate the clutch to engage the wind motor with the take-up roll upon the partial uncovering thereof, and a valve to connect a controlling element of said last named means with the stop mechanism.

5. In an automatic musical instrument the combination of a spool for the note sheet, a tracker, a take-up roll to connect the note sheet from the spool, a wind motor, a clutch to connect the wind motor alternatively with the spool or the take-up roll, a stop mechanism, automatic means to operate the clutch to engage the wind motor with the spool operable by the opening of a tracker vent, means to operate the clutch to engage the wind motor with the take-up roll upon the partial uncovering thereof, a valve to connect a controlling element of said last named means with the stop mechanism, and means effective upon the operation of said last

named clutch operating means to render the tracker controlled clutch operating means ineffective.

6. In an automatic musical instrument the combination of a spool for the note sheet, a tracker, a take-up roll to receive the note sheet from the spool, a wind motor, a clutch to connect the wind motor alternatively with the spool or take-up roll, a stop mechanism, automatic means to operate the clutch to engage the wind motor with the take-up roll upon the partial uncovering thereof, and a valve operable simultaneously with said last named means to shut off communication between said tracker controlled clutch operating means and the said tracker vent.
- 20 7. In an automatic musical instrument the combination of a spool for the note sheet, a tracker, a take-up roll to receive the note sheet from the spool, a wind motor for driving the note sheet, a clutch for connecting the wind motor alternatively with the spool or the take-up roll, pneumatic means having connection with a tracker vent for engaging the clutch with the spool to rewind the note sheet, and pneumatic means having connection with a controlling element adjacent the take-up roll and operable by the partial uncovering thereof to engage the clutch with the take-up roll to feed the note sheet forward, the operation of said last named means rendering ineffective the opening of said rewind controlling tracker vent.
- 30 8. In an automatic musical instrument the combination of a spool for the note sheet, a tracker, a take-up roll to receive the note sheet from the spool, a wind motor for driving the note sheet, a clutch for connecting

the wind motor alternatively with the spool or the take-up roll, clutch operating means to engage the clutch with the spool for rewinding including a primary valve operable 45 from a tracker vent and a secondary valve, pneumatic means having connection with a controlling element adjacent the take-up roll and operable by the partial uncovering thereof to engage the clutch with the take-up roll 50 to feed the note sheet forward, and a valve operated by the controlling element adjacent the take-up roll to close communication between said primary and said secondary valves. 55

9. In an instrument of the character described, the combination of a spool for the note sheet, a tracker, a take-up roll to receive the note sheet from the spool, said roll being provided with an annular groove adjacent one end, automatic motor stop mechanism including a valve controlling lever adapted to move into said annular groove when it is uncovered by the note sheet, note sheet driving means including a clutch, pneumatically operable clutch throwing means, and means providing an operative connection between said valve operating lever and the clutch throwing means. 65

10. In an instrument of the character described, the combination of means for automatically rewinding the note sheet, means for automatically replaying said note sheet, and pneumatic means coöperating with one of said other means for automatically actuating motor-stop mechanism under predetermined conditions. 70

In testimony whereof, I have signed my name to this specification this 28th day of February, 1918.

CHARLES F. STODDARD.
